UNITED STATES PATENT OFFICE.

ALBERT J. MEIER, OF ST. LOUIS, MISSOURI.

TOOL.

SPECIFICATION forming part of Letters Patent No. 773,214, dated October 25, 1904.

Application filed January 9, 1904. Serial No. 188,402. (No model.)

To all whom it may concern:

Be it known that I, ALBERT J. MEIER, a citizen of the United States, residing at the city of St. Louis, State of Missouri, have invented a certain new and useful Improvement in Tools, of which the following is a full, clear, and exact description, such as will enable others skilled in the art to which it appertains to make and use the same, reference being had to the accompanying drawings, forming part of this specification, in which—

Figure 1 is a side elevation, partly in section, certain of the parts being broken away, the full lines indicating the tool in closed or operative position and the tool being shown by broken lines in open position. Fig. 1^a is a front view of the jaws. Fig. 2 is a rear elevation, partly in section, a portion of the securing member being broken away. Fig. 3 is a sectional elevation on about the line 3 3 of Fig. 1; and Figs. 4, 5, and 6 are views of the character of Fig. 3, said views illustrating modifications.

This invention relates to improvements in tools.

One object is to provide a tool-holder for tools having pivoted handles whereby the tool-points can be carried in said holder and connected to the tool proper in such manner that such tool proper forms a handle for the tool-points. Of course the tool proper can be merely a handle, or its jaws can be adapted to be used as pliers or other instruments.

A further object is to provide means whereby when the holding member is not in use it is held out of the way of the operator.

To these ends the invention consists in the various matters hereinafter described and claimed.

Referring now more particularly to the drawings, 11 indicate handles pivoted at 2 and having jaws 3 secured thereto, all as will be readily understood. To one of the handles is pivotally connected a holding member 4, which is adapted to engage the other handle for the purpose of holding said handles in such position that the jaws 3 are firmly closed, such a holding member being well understood in the art. Extending in the space between the handles is a receptacle or tool-holder 5,

which is merely a conveniently-shaped box having what may be termed its "forward" end closed by the wall 6, while its open rear end is conveniently closed by means of the before-mentioned holding member 4. Tool-points being carried in said holder or receptacle 5, any desired point can be removed when the holding member or catch 4 is thrown into open position, and the tool-point thus removed can be clamped between the jaws 3 in a manner which will be readily understood, the handles being again fastened together by throwing the catch or holding member 4 into closed handle-engaging position.

Manifestly the receptacle 5 can be supported between the handles in many ways. Preferably each handle is curved in cross-section, as illustrated in Fig. 3, and the receptacle 5 is connected to one of the handles by rivets 7. Of course the receptacle could be not attached to either of the handles, but merely be received between said curved handles, as shown in Fig. 6, or the receptacle could be produced by making its walls 8 integral with or continuations of one of the handles, 1^a, as shown in Fig. 5. Again, as shown in Fig. 4, one of the handles, 1^b, could have its edges extending inwardly, as shown at 9, the receptacle 5^b being provided with longitudinal grooves adapted to receive inwardly-extending portions 9 of the handle. 80

The jaws 3 are preferably of such character that they can be employed for purposes other than that of holding the tool-points—*e. g.*, the jaws illustrated can be used as pliers. When so used, it sometimes happens that the jaws 85 are frequently opened and closed, and it is therefore undesirable to lock these jaws together by means of the holding member 4. Were the holding member 4 merely loosely mounted upon its pivot 10 such holding member would fall outwardly and get in the way of the user. I preferably, therefore, provide means whereby when the holding member is not in use it is held in a position out of the way of the user. As illustrated in the accompanying drawings, a spring 11 is coiled about the pivot-pin 10 and has one end connected to the holding member 4 and its other end connected to the handle 1, upon which said holding member is pivoted, said spring tending to 100

force the holding member inwardly into the position indicated by heavy dotted lines in Fig. 1. Therefore if the handles be opened when the holding member is not in holding or operative position the spring immediately throws the holding member inwardly and retains the same out of the way of the user. Of course this holding member, with its means for holding the same out of the operator's way, can be employed advantageously even when the tool-box or receptacle 5 is omitted.

I am aware that minor changes in the construction, arrangement, and combination of the several parts of my device can be made and substituted for those herein shown and described without in the least departing from the nature and principle of my invention.

Having thus described the invention, what is claimed as new, and desired to be secured by Letters Patent, is—

1. The combination with a tool having pivoted handles, and jaws connected to said han-

dles, of a tool-receptacle extending between said handles and provided with an opening for the passage of tool-points, and a holding member for holding said handles together and extending over said opening of said tool-receptacle in proximity thereto to form a closure therefor; substantially as described. 25

2. The combination in a tool having pivoted handles, of a holding member coöperating with said handles, and a spring connected to one of said handles and to said holding member and tending to force said holding member into folded position against one of said handles; 30 substantially as described.

In testimony whereof I hereunto affix my signature, in the presence of two witnesses, this 7th day of January, 1904.

ALBERT J. MEIER.
